UNITED STATES PATENT OFFICE.

ALBIN WILBERG, OF DE KALB, ILLINOIS.

PIANO-LOCK.

1,088,500.

Specification of Letters Patent. Patented Feb. 24, 1914.

Application filed May 3, 1913. Serial No. 765,297.

To all whom it may concern:

Be it known that I, ALBIN WILBERG, a citizen of the United States, residing at De Kalb, in the county of Dekalb and State of Illinois, have invented new and useful Improvements in Piano-Locks, of which the following is a specification.

This invention relates to that class of locks which are designed for use upon pianos and organs and which embody a vertically and laterally movable bolt, a key actuated cam for operating the bolt and a spring for retaining the cam in its adjusted positions, the object of the invention being to provide simple and effective guiding and controlling means between the bolt and lock casing by which the end of the bolt will be positively disposed and maintained in alignment with the face plate of the casing, a positive locking and unlocking action secured, when the bolt is projected and retracted, and the necessity of trimming the parts of the lock avoided to secure proper motion and arrangement of the bolt.

The invention consists of the features of construction, combination and arrangement of parts hereinafter fully described and claimed, reference being had to the accompanying drawings, in which:

Figures 1, 2 and 3 are vertical sections through a lock casing showing the bolt in different positions. Fig. 4 is a detail section on line 4—4 of Fig. 2.

Referring to Figs. 1 to 4, inclusive, of the drawings, 1 designates a lock casing having a face plate 2 provided with a slot or opening 3 through which moves the keeper engaging portion of the bolt 4. The body 5 of the bolt is provided, as usual, with a recess to receive the actuating arm 6 of the cam 7, which is journaled upon the casing and provided with the keyhole 8. The recess in the body 5 is so shaped as to provide portions adapted to be engaged by the arm 6 to lift the bolt and move it laterally in one direction of movement of the cam, and to depress the bolt and return it to normal position, in the opposite direction of movement of the cam. The cam is provided with the usual retaining lug or projection

10 adapted for engagement with a spring 11, whereby the cam is maintained in its positions of adjustment.

Ordinarily, in locks of this character, the cam is relied upon to maintain the retracted bolt in proper position with its outer end flush with the face plate, but when the parts are carelessly made or are not accurately fitted together, or wear occurs, the bolt is liable to be out of proper position or to have an improper range of motion, thus rendering it necessary to trim or refit the parts in order to make the bolt positive and effective in its locking and releasing actions. In order to overcome these objections, I provide either the front wall or the back wall 55 of the casing with a guide slot 12 inclined at an oblique angle to the vertical path of the bolt, and which receives a tongue or projection 13 formed upon the lower cam engaging arm of the bolt, whereby the bolt is guided in its vertical movements and at the same time is permitted to move laterally and is properly guided in its lateral movements. 60 The upper and lower end walls 14 and 15 of 70 this slot serve as stops for coaction with the tongue or projection 13, whereby the movement of the bolt is positively arrested when the bolt is fully projected or retracted. The stop surface 15 further limits the inward 75 movement of the bolt at the time when the outer end of the bolt lies flush with the face plate 2, thus obviating the necessity of trimming the parts to secure a proper arrangement and movement of the bolt, and at the same time providing for a positive and certain locking and releasing action of the bolt without the necessity of making other and complex provisions therefor. 80

I claim:

A piano lock comprising a casing having a face plate provided with a bolt slot, said casing also having one of its walls provided with a guide slot inclined at an oblique angle to the vertical plane of the bolt slot, a bolt 95 movable vertically and laterally through said bolt slot, said bolt having a bifurcated body portion forming a cam surface and projecting and retracting arms, a key actuated cam for coöperation with said cam sur- 100

face and arms to project and retract the bolt, and a tongue or projection upon the retracting arm of the bolt movable in said inclined bolt slot, whereby the bolt is guided positively in its vertical and lateral movements and held when retracted with its locking end flush with the face plate.

In testimony whereof I affix my signature in presence of two witnesses.

ALBIN WILBERG.
